UNITED STATES PATENT OFFICE.

LA VERNE NOYES, OF CHICAGO, ILLINOIS, ASSIGNOR TO AERMOTOR COMPANY, OF CHICAGO, ILLINOIS, A CORPORATION OF ILLINOIS.

WINDMILL.

1,163,682.

Specification of Letters Patent. Patented Dec. 14, 1915.

Application filed February 5, 1915. Serial No. 6,323.

To all whom it may concern:

Be it known that I, LA VERNE NOYES, citizen of the United States, residing at Chicago, in the county of Cook and State of Illinois, have invented a certain new and useful Improvement in Windmills, of which the following is a full, clear, concise, and exact description, reference being had to the accompanying drawings, forming a part of this specification.

My invention relates to wind mills and has a number of objects and advantages in view.

By means of my invention I am enabled to reduce friction between some of the engaging relatively movable parts. To this end the force which is employed to furl the mill and actuate the brake is applied in an upward direction longitudinally of the tower, such force tending to lift the mill head from rather than press it toward its step bearing, though the invention is not to be limited to this method of adjustment. In carrying out the invention, the furling mechanism desirably applies the brake during the final part of the vane folding movement.

I will explain my invention fully by reference to the accompanying drawings showing the preferred embodiment thereof and in which—

Figure 1 is a view in elevation, partially in section, of a wind mill embodying the invention; Fig. 2 is a somewhat diagrammatic view showing my lever arrangement; Fig. 3 is a view on line 3 3 of Fig. 1; Fig. 4 is a view in elevation of the upper part of a mill; Fig. 5 is a view on line 5 5 of Fig. 3; Fig. 6 is a detail; and Fig. 7 is a detail.

Like parts are indicated by similar characters of reference throughout the different figures.

The wind wheel 1, having a horizontal axis, is mounted upon a shaft which carries spur pinions 2 in mesh with spur gears 3 that operate pitmen 4 having connection at their upper ends with the load rod 5. The wind wheel is mounted upon a mill head 6 which is afforded an upright axis of rotation by being mounted upon the shouldered end of a stationary vertical pipe 7 at the upper end of the mill tower and through which pipe the load rod passes.

The mill vane 8 is journaled at 9 upon the mill head to swing about an upright axis, the

vane being moved toward and from the wind wheel when the latter is respectively to be placed out of and in the wind, spring buffers 10 cushioning the vane in the final portions of its swinging movements.

A swinging arm 11 is afforded an upright axis of movement by being mounted upon a vertical bearing shaft 12 fixed upon the mill head with the load rod between and preferably substantially equidistant from the mounting shafts 9 and 12. The long branch 65 of arm 11 is flexibly connected with one end of link 13 whose other end moves a finger 13¹, operatively forming a part of the link, which operates to engage and move the vane toward the wheel in the furling operation, 70 but from which finger the vane may move toward the wheel in governing. A lever rod 14 connects a vertically movable furling collar 15 with the arm 11 near the connection of said arm with link 13, which link is 75 also preferably a rod. The vane shaft 9 is located between the vane ends of rods 13 and 16 that afford flexible connection between the furling collar 15 and the outer ends of an arm 8¹ pivoted between its ends upon 80 upright shaft 9. In the furling operation, link 13 pulls upon one end of arm 8¹ and rod 16 pushes upon the other end of this arm to cause finger 13¹ to push the vane 8 to a closed position. The form of flexible connection between the rod 14 and arm 11 and of lever rod 16 with the arm 8¹ may be generally of the nature illustrated in Fig. 6. The lower ends of lever rods 14 and 16 are bent to extend horizontally there to be 90 journaled in horizontal bearings 17 formed on top of the furling collar 15 and on opposite sides of its axis and equidistantly from its center. The collar 15 is in assembly with a flanged sleeve 18 (loosely surrounding pipe 7), the flange of the sleeve 18 having connection with the upper ends of push rods 19 whose lower ends are connected with one end of a lever 20 whose other end carries a pull wire 21 accessible from the ground. 100 The collar 15 and the rods 14 and 16 will turn with the head and with reference to sleeve 18 which is only vertically movable. When the wire 21 is pulled downwardly (after which action it is hooked at its lower 105 or ground end), the rods 19 are consequently pushed upwardly to cause the flange of sleeve 18 to push the furling collar up, to

swing the mill vane from its position when the wheel is in the wind to a position in which the wheel is out of the wind, this latter position being indicated by dotted lines in Fig. 2. Because of the illustrated location of the shaft 9 between the adjacent ends of lever rods 14 and 16 and the manner in which these lever rods are connected with the furling collar, the force applied by the 10 diametrically opposite upwardly pushed rods 19 is so distributed that the furling collar will not have forceful lateral engagement with the sleeve 18 and the sleeve will not have binding engagement with the pipe. 15 The arm 11 of the furling mechanism is also instrumental in applying braking pressure to the wind wheel when the vane is nearly completely folded toward the wheel. For this purpose the arm 11 has a short branch 20 22 adapted to ride upon the free end of a spring brake band 23 which passes about the brake drum hub portion 24 of the wind wheel and has its anchored end secured to the mill head. 25 In order that the wind mill may be properly sensitive to changes in direction of the wind it is essential for the mill head to turn upon its vertical axis with the utmost freedom. By making use of an upward force 30 transmitted through the push rods 19, furling of the mill is accomplished without increasing the frictional resistance with the turning of the mill head upon its bearing. The pressure applied to the furling collar 15 35 is removed from rather than exerted upon the step bearing. Similarly the braking force, upwardly applied, is not exerted upon but is removed from the step bearing. When the wheel is in the wind the push rods 19 40 will drop sufficiently to space the flanged sleeve 18 vertically apart from the furling collar 15 to an extent that will eliminate material frictional contact between this sleeve and collar while the mill head is turning. 45 When the mill has been furled by the upward movement of the furling collar the lever rods 14 and 16 have been brought almost to the horizontal so that the downward pressure exerted by them is very slight and consequently the pressure tending to produce 50 friction between the furling collar, when rotating, and flanged sleeve is correspondingly small. In one broad aspect of the invention, therefore, the flanged sleeve and the pushing rods 19 constitute a pushing element, which 55 when pushed upwardly, will furl the mill and apply the brake, though the invention is not to be limited to a construction in which the rods 19 are pushed. 60 While I have herein shown and particularly described the preferred embodiment of my invention I do not wish to be limited to the precise details of construction shown as changes may readily be made without departing from the spirit of my invention, but 65

Having thus described my invention I claim as new and desire to secure by Letters Patent the following:

1. A wind mill including a wind wheel; a mill head upon which the wheel is mounted to turn; a swinging arm mounted upon the mill head; a brake for checking the rotation of the wheel when out of the wind and inclusive of a brake drum driven by the wind wheel and a brake drum engaging brake band positioned to be operable by said arm when the wind mill is nearly placed out of the wind; and means for applying the brake band to the brake drum inclusive of a vertically movable and rotatable member and a rod directly connecting this member and the arm. 70
2. A wind mill including a wind wheel; a mill head upon which the wheel is mounted to turn; a mill vane mounted to swing upon the mill head; a swinging arm mounted upon the mill head; a link serving to connect the vane and arm; and means for applying power to fold the vane toward the wheel and inclusive of a vertically movable and rotatable member and a rod flexibly coupling this member and said arm, and another rod flexibly coupling the mill vane with the opposite side of said member. 80
3. A wind mill including a wind wheel; a mill head upon which the wheel is mounted to turn; a mill vane mounted to swing upon the mill head; a swinging arm mounted upon the mill head; a link serving to connect the vane and arm; and means for applying power to fold the vane toward the wheel and inclusive of a vertically movable member and a rod flexibly coupling this member and said arm and another rod flexibly coupling the mill vane with the opposite side of said member. 90
4. A wind mill including a wind wheel; a mill head upon which the wheel is mounted to turn; a mill vane mounted to swing upon the mill head; and means for applying power to fold the vane toward the wheel and inclusive of a vertically movable and rotatable member and rods having flexible connection with this member upon opposite sides of its axis and in actuating relation with the mill vane. 100
5. A wind mill including a wind wheel; a mill head upon which the wheel is mounted to turn; a mill vane mounted to swing upon the mill head; and means for applying power to fold the vane toward the wheel and inclusive of a vertically movable and rotatable member and rods having flexible connection with this member upon opposite sides of its axis and in actuating relation with the mill vane and disposed to have substantially equal actuating influence upon the vane. 110
6. A wind mill including a wind wheel; a mill head upon which the wheel is mounted

to turn; a mill vane mounted to swing upon the mill head; and means for applying power to fold the vane toward the wheel and inclusive of a vertically movable member and rods having flexible connection with this member upon opposite sides of its axis and in actuating relation with the mill vane.

7. A wind mill including a wind wheel; a mill head upon which the wheel is mounted
10 to turn; a mill vane mounted to swing upon the mill head; and means for applying power to fold the vane toward the wheel and inclusive of a vertically movable member

and rods having flexible connection with this member upon opposite sides of its axis and 15 in actuating relation with the mill vane and disposed to have substantially equal actuating influence upon the vane.

In witness whereof, I hereunto subscribe my name this third day of February, A. D., 20 1915.
